UNITED STATES PATENT OFFICE.

ROBERT G. CLARK, OF BROOKLYN, NEW YORK, ASSIGNOR TO THE ADJUSTRITE COMPANY, INC., OF NEW YORK, N. Y., A CORPORATION OF NEW YORK.

ADJUSTABLE WINDOW-CURTAIN.

1,262,175.

Specification of Letters Patent.

Patented Apr. 9, 1918.

Application filed August 31, 1916. Serial No. 117,823.

To all whom it may concern:

Be it known that I, ROBERT G. CLARK, a citizen of the United States, residing in the borough of Brooklyn, county of Kings, and State of New York, have invented a new and useful Improvement in Adjustable Window-Curtains, of which the following is a description.

This invention relates to means for dressing windows, doors, or other openings in buildings, and particularly has reference to window-shades and curtains and the means and devices useful for the purpose of raising and lowering the same.

Among the objects of my invention may be noted the following: To provide simple, effective and durable means for raising and lowering curtains of all kinds, whether on windows, doors, or other openings; to provide a means by which raising and lowering curtains are rendered effective, certain and easy by the manipulation of simple devices arranged in coöperative relation with the curtains; to provide a novel form of friction-block for curtain-cords; and to provide certain details of construction and devices by which the foregoing objects are attained.

In order that my invention may be clearly understood, I have provided drawings wherein:

Figure 1 is a front elevation of a window-frame provided with my invention, the view being broken both vertically and transversely in order to curtail the same;

Fig. 2 is a top-plan view of the channel-bars and corner-blocks arranged in coöperative relation, the view being broken in the middle to curtail the same;

Fig. 3 is a bottom-plan view of the structure of Fig. 2, sectioned on line 3—3, Fig. 1;

Fig. 4 is a section substantially on the line 4—4 of Fig. 2;

Fig. 5 is a perspective of a portion of the top channel-bar;

Fig. 6 is a perspective of a portion of one of the side channel-bars;

Fig. 7 is a top-plan of the left corner-block;

Fig. 8 is a plan of the block of Fig. 7 turned over one-quarter to the right;

Fig. 9 is a bottom-plan of the block of Fig. 7;

Fig. 10 is a plan of the reverse of Fig. 8;

Fig. 11 is a top-plan of the right corner-block;

55

Fig. 12 is a view illustrative of various ways in which the curtain may be disposed according to, and through the medium of, my invention;

Fig. 13 is a section substantially on the 60 line 13—13 of Fig. 1;

Fig. 14 is an enlarged detail of the operator and coöperating parts shown in Fig. 13; and

Fig. 15 is a section substantially on the 65 line 15—15 of Fig. 1.

This invention is an improvement on that of U. S. patent to Barnard, No. 1,177,918, April 4, 1916, and embodies constructional features which do away with the weights, 70 stops and pulleys shown in said patent, and provide improved features which tend to cheapness of production, effectiveness in operation, strength and durability.

Referring to the drawings, the numeral 1, 75 Fig. 1, indicates the sill of an ordinary window, the sash-frames of which have been omitted in order to avoid confusion and simplify the illustration of the present invention, a broken line indication in Figs. 1 80 and 4, however, being given of the top sash-frame, the same being indicated by 2. 3 is the top window-sash and 4 is the bottom window-sash; or, if the invention be applied to a door-frame, the same may indicate the 85 upper and lower portions of the door.

The top channel-bar 5 is provided with a plurality of apertures 6, for the reception of screws 7, or other fastening means by which said channel-bar may be secured to the top-frame of the sash-frame, see Figs. 2 to 5. The opposite ends of this channel-bar are extended, as at 8, beyond the side-flanges 9 thereof, and adjacent the front edge of said extensions 8 elongated slots 10 may be 90 provided, through which screws 11 work for the purpose of securing the right and left corner-blocks 12 and 13 to the extensions 8. The channel-bar and blocks make the primary unit of my structure. The screws 100 11 enter screw-threaded apertures 14 of said blocks, see Figs. 7 and 11. By this means, the blocks may be primarily secured to the top channel-bar 5 and the structure, as a unit, set in place, as shown in Figs. 1, 2 and 105 3; and, if it be found that the blocks are not

accurately set for the distance between the side sash-frames, adjustment can be readily made by loosening the screws 11 and tapping the blocks one way or the other.

5 Side channel-bars are provided to extend longitudinally of the sash-frame, with the lower end of each of said side channel-bars resting upon the sill 1. Details of the side channel-bars are shown in Figs. 2, 3, 4, 6, 10 13 and 14, wherein 15 is the side which is secured in suitable manner, as by screws 16, to the side window-frames. 17 is the back member which abuts the end of inner flange 9, the latter being secured to a 15 corner-block 12 or 13, by means of a screw 19 passing through the slot 20 and into the hole 19^a in one end of the corner-blocks. 21 is the front member provided with the angularly-arranged portions 22 and 23, the 20 latter being a flange adapted to set behind the front flange 9 of the top channel-bar, as at 24, Fig. 3. The angular member 22 is provided with a T-shaped extension or 25 guide 25, extending longitudinally of the said side channel-bar and which is adapted to be received in a similarly-shaped slot in the corner-blocks, as presently described. The side channel-bars are the secondary units of my structure and can be readily 30 set in place and secured to the primary unit as rights and lefts, as clearly shown in Figs. 2, 3 and 4.

The corner-blocks, which form a part of the primary unit of my structure, have most 35 features in common; but, by reason of the mode of adjustment of the cords and the universality of disposition of the shade or curtain, the right and left blocks differ in some small details, as will now be described. 40 Figs. 7 to 10, inclusive, illustrate four positions of the left corner-block, while Fig. 11 illustrates the operative position of the right corner-block. The corner-blocks are rectangular in form and the left corner-block, in its top surface, is provided with a groove 26, which begins at the right side of the block, extends toward the left side thereof, turns substantially at a right-angle, and then extends obliquely, as at 26^a, toward 45 the front of the block, and terminates in a vertical aperture 27, extending from top to bottom of the block. Another groove 28 starts at the right side of the block and extends parallel with the groove-portion 26 and 50 culminates in a vertical aperture 29, extending through the block. A third groove 30 extends from a vertical aperture 31, near the bend of the groove 26 and 26^a and obliquely toward the front right 55 corner of the block, where it terminates in a vertical aperture 32. These several grooves and apertures are deep and smooth and well-rounded so as to enable the cords, presently described, to slide freely therein with 60 comparatively little friction, although, as will

be presently shown, some friction is desirable for operative purposes. The left block 13 is also provided with the oblong aperture 33, extending from top to bottom thereof and adapted to receive the head 25 of 70 the T-shaped extension on the member 22 of the side channel-bar. A vertical slot 34 is also cut into the right side of the block 13, adjacent the aperture 14, the same being for the reception of the end 35 of 75 the front member 9 of the top channel-bar, and this slot is extended across the top of the block as a shallow groove 36, for the reception of the depending flange 37, on the front edge of the extension 8, of the 80 top channel-bar, see Figs. 2 and 5.

Viewing Fig. 8, which represents the block of Fig. 7, turned one-quarter to the right, it will be seen that the top surface of the block, in which the various grooves are disposed, is provided with two levels, the lower level being indicated by 38, which is for the reception of the extension 8, of the top channel-bar, so that when said block is secured to said extension, the top of the latter and the surface 39, will be flush and will in consequence fit snugly and evenly against the top window-frame member. The part 40, of the block, is the depending or bottom portion in which the slot 33, 95 is formed and which is made sufficiently extensive to receive the upper end of the T-shaped flange or extension 25 of the side channel-bar, see Figs. 3 and 4. Fig. 9, 100 which is the bottom of the block of Fig. 7, shows that the bottom of the block is substantially smooth though in two levels on account of the depending portion 40. Fig. 10, shows the block in the reverse of Fig. 8 or the right side of the block of Fig. 105 7, and all the features thereof are now clearly understood. This figure shows substantially the depth of the grooves 26 and 28.

The right corner block 12, is shown in Fig. 11, and is in all respects the same as 110 the left corner-block 13, excepting that the grooves and apertures in the top surface thereof are differently disposed in order to carry out the desired raising and lowering functions of the manipulating cords as presently described. In this figure, a groove 41 starts at the left side of the block and extends toward the right side, having a turn about midway of the block and extending a short distance toward the front thereof as at 42, the groove terminating in the aperture 43, extending through the block from top to bottom. Another groove 44, extends from the left side of the block with a bend a short distance from said side and 115 then extends toward the front of the block, terminating in an aperture 45, extending vertically from top to bottom of the block. A third groove 46, extends from a point between the other two grooves and about mid- 120

way of the block, and from an aperture 47, terminating near the front of the block in an aperture 48, both of which apertures extend vertically through the block. Adjacent to the groove 46, the aperture 14, is provided for the screw 11, which passes through the slot 10, by which the block is secured to the extension 8 of the top channel-bar. An oblong aperture 49, similar to the one 33, in the block 13, is provided for the reception of the head 25, of the T-shaped extension of the side channel-bar. A slot 50, similar to the slot 34, in the block 13, is provided for the same purpose, as is also a groove 51, similar to the groove 36 in the block 13.

For raising and lowering the shade or curtain two actuators are employed, the same being made as rights and lefts as shown in

Fig. 1. They are identical in structure, so that a description of one will answer for both; and, referring to Figs. 13 and 14, it will be seen that the actuator consists of the elongated curved portion 53, made tubular more or less of its length, for containing a weight or heavy filling 54. The actuator is at its inner side provided with a T-shaped slot 55, adapted to receive the T-shaped extension 25 of the side channel-bar, said slot 55 being formed with a removable wall 56, secured by screws 57, to the actuator. Thus the actuator can be readily applied to and removed from the side channel-bar whenever required. The grooved portion of the actuator is provided with apertures 58, through which the manipulating cords are extended as presently described. For insertion or removal of the filling or weight 54, the actuator at its upper end may be provided with an ornamental cap or closure 59, which may be screwed into place or frictionally applied.

Viewing Figs. 1, 13 and 15, it will be seen that the curtain 60 is formed into a number of plaits to make an extensible and collapsible accordion structure. The upper and lower ends are extended between bars 61, which clamp the said curtain tightly when said bars are set within the spring clamp or holder 62; that is to say, the holder 62, is a hollow rectangle split longitudinally, to provide an opening through which the material of the curtain may extend into coöperation with the clamping bars 61, and when said bars are inserted within the spring-clamp, they will be together with the curtain, securely held. The adjacent edges of the clamp will also engage the curtain material. When it is desired to renew or change the curtain, top and bottom clamps 62, are brought together as closely as possible and the entire structure is then tilted at one end, so as to raise the same within one of the side channel-members to withdraw the structure from the latter. Then the bars 61, can be removed

from the clamp members 62, and the curtain edges released. Another curtain may then be secured in place as will be readily understood. A cord and tassel 63, is secured to the bottom of each of the actuators 70 by which to operate the curtains when said actuators are raised too high to be grasped by the hand. If the actuators are within reach, however, it will be quite natural to grasp the same for the purpose of raising or lowering the curtain; and it will be understood that the angular disposition of the actuators, as mounted upon the T-shaped guides 25, and the angular relation of said guides to the side channel-bars, places said actuators 80 in position to enable them to be readily grasped for the purpose of operating the curtains.

Now referring to Figs. 1, 2, 3, 4 and 12, the mode of operation of my invention will 85 be readily understood, and, referring to Fig. 12, it will be seen that the shade, curtain or screen may be adjusted to any position desired; that is to say, it may be adjusted wholly at the bottom or wholly at the top of 90 the opening, window or door; it may entirely cover the latter, or may be adjusted so as to cover the upper half, or the lower half, or any intermediate portion and to any extent desired. Now viewing Figs. 1, 2 and 95 3, cord 64 will be seen to be secured in any suitable manner to the right-hand actuator 53, and to extend upwardly through the same and through the aperture 48 of the right corner block 12, and thence downwardly through the aperture 47 of said block, within the right-side channel-bar, through the top clamp 62 and curtain and secured in any suitable manner to the bottom clamp of the curtain as at 65. Another 100 cord 66, is secured in any suitable manner to the right-hand actuator and extends upwardly through the same and through the aperture 45, of the right corner-block, and thence to the left in the groove 44 and with- 105 in the top channel-bar to the left corner-block, passing through groove 28 and downwardly through the aperture 29, and thence downwardly within the left side channel-bar, through the top clamp-bar 62, and the 110 curtain and then secured to the bottom clamp bar as at 67, in any suitable manner. By these media, the bottom clamp-bar may be primarily lifted and the entire curtain raised, it being possible to raise the curtain 115 bodily into any position desired from bottom to top of the window, by merely drawing downwardly upon the right hand actuator or its tassel cord 63. The left hand actuator has secured thereto, in any suitable 120 manner, a cord 68, which extends upwardly through the actuator, through the aperture 32 in the left hand block, and downwardly through aperture 31 of said block and with- 125 in the left side channel-bar to the top clamp 130

bar of the curtain, to which bar it is secured as at 69, in any suitable manner. The left hand actuator also has secured thereto in any suitable manner, a cord 70, which extends upwardly through the actuator and through the vertical aperture 27 of the left corner block, and thence through the grooves 26^a and 26 of said block, and then extends through the top channel-bar to the right corner block, entering the same through the groove 41, and extending downwardly through the aperture 43 of said block and through the right side channel-bar to the top curtain clamp, to which it is secured as at 71 in any suitable manner. By these media, the top bar of the curtain, together with the curtain and the lower bar may be lifted by pulling down on the left hand actuator, so as to raise the top bar and the curtain to the full or a partially extended position. By manipulating either one or the other of the actuators, the curtain or shade can be raised and lowered into any of the positions shown in Fig. 12, and to many other positions as will be readily understood. The various cords, the runs of which have been just described, lie in the deep grooves of the right and left corner blocks and cling thereto with considerable friction, and yet with not sufficient friction as to prevent the ready and free manipulation or raising and lowering of the curtain. By reason of this frictional engagement of the cords, in the various grooves, extending between and continuing the several apertures, the actuators do not have to be made very heavy, since the frictional engagement of the cords in the grooves of the several blocks and the weight of the actuators will support the curtain, regardless of its weight, in any desired position. It will, therefore, be understood that the actuators are weighted only to an extent sufficient to counterbalance the weight of the curtain, including its top and bottom bars, taking into consideration the frictional engagement of the cords with the corner blocks. Hence, the structure of the actuators, which enables a weight of any desired amount to be inserted therein through the top thereof, by removing the cap 59.

Stress is laid upon the fact that in accordance with my invention, frictional devices are employed as a part of the primary unit of the structure in contradistinction to anti-frictional devices, such as pulleys or other movable devices which would enable the cords to readily run and freely slide. Furthermore, stress is laid upon the fact that the actuators are merely counterbalancing devices and are not in any sense automatic operating means, since in addition to their form and disposition, which enables them to be readily grasped, they simply operate to sustain the weight of the curtain and its

top and bottom bars as a counterbalance, and to enable the very easy manipulation of the cords, notwithstanding the frictional engagement thereof with the corner blocks. Stress is also laid upon the fact that to raise and lower the curtain, one or the other of the actuators has simply to be drawn downwardly, this operation resulting in drawing the other one upwardly under certain conditions, as shown in Fig. 12; and the manipulation of the actuators, together with the connections of the cords with the curtain as described, enables the latter to be raised and lowered uniformly from side to side of the window, door or opening, thus always maintaining the curtain in the proper position, and in consequence avoiding friction of the ends of the curtain and its clamps, within the side channel-bars. According to the material used in the curtain, the actuators will be weighted, to produce the counterbalancing effect, and when a heavy curtain is substituted for a light curtain, a little more weight would be added to the actuators by dropping the same therein, after removing the cap 59. If a light curtain is substituted for a heavy one, sufficient weight will be removed from the actuators.

To set my structure in place, it is only necessary to apply the corner-blocks to the top channel-bar, and then screw this unit to the top sash-member of the window or door. Then the side channel-bars are set in place. The cords may be laced through the blocks, either before or after the units are secured in place, since the grooves and apertures are smooth, and it is only necessary to push the cord, which is usually of stiff material, into the proper aperture. After the cords have been laced through the several blocks, they can be readily attached to the curtain, and the latter then set in place by an operation, the reverse of that described for removing the same from the side channel-bars.

Having thus described my invention, what I claim and desire to secure by Letters Patent is:

1. In combination with a curtain, side channel-bars for guiding the ends of the curtain, a plurality of friction imposing corner-blocks having grooves therein extending at angles to each other, said blocks being arranged in operative relation to said channel-bars, lifting cords attached to the top and bottom of the curtain and sliding through said grooves for frictionally guiding the cords through the corner-blocks, and means by which to raise and lower the curtain through the medium of said cords and act as a partial counterbalance for the weight of the curtain.

2. In combination with a curtain, guiding means for the ends thereof, means for raising and lowering the curtain including cords

and actuators therefor which latter also act as a partial counterbalance for the curtain, and means, including corner-blocks having a plurality of angularly arranged grooves 5 therein for guiding the cords and producing friction thereon, whereby control of the curtain may be obtained when it is raised or lowered.

3. In combination with side channel-bars, 10 forming guides for a curtain, a unit structure composed of a top channel-bar, provided with fixed friction-producing blocks at its opposite ends, the said unit structure connecting the guiding means and interacting 15 with the same to form guiding means for curtain manipulating cords.

4. In combination with a curtain of predetermined weight, guiding means for the ends thereof, cords attached to the curtain 20 for raising and lowering the same, positive friction-producing means for guiding the cords, and weighted actuators connected to the cords, the weight of the actuators, plus the friction of the guiding means upon the 25 cords, substantially counterbalancing the weight of the curtain whereby to produce easy manipulation of the curtain.

5. An actuator for curtain-raising means, 30 comprising a hollow body having a weight held therein, and having a guiding-slot therein, one of the walls of which slot is

formed by a removable plate, and means for securing said plate removably to the actuator.

6. A block for curtain-raising means, comprising a rectangular body, having in one of its surfaces a plurality of grooves arranged at an angle to each other, each terminating in one or more apertures extending through the body of the block at an 40 angle to the groove.

7. A block for curtain-raising means, composed of a rectangular body, having in one of its surfaces a plurality of curved grooves arranged at an angle to each other, each terminating in an aperture extending through the body of the block at an angle to the 45 groove.

8. A block for curtain-raising means, comprising a rectangular body, having in each 50 of its surfaces a curved groove and a straight groove at an angle to each other, each of said grooves terminating in an aperture extending through the body of the block at an angle to the groove.

9. A block for curtain-raising means, composed of a rectangular body, having a plurality of grooves arranged at an angle to each other, and which grooves terminate at a flat wall or face of the block. 55

ROBERT G. CLARK.
